(57) **CLAIM**

The ornamental design for a control panel for an automobile, as shown and described.

DESCRIPTION

FIG. 1 is a perspective view of a control panel for an automobile of my design;

FIG. 2 is a front view thereof;

FIG. 3 is a top plan view thereof;

FIG. 4 is a right side view thereof; and,

FIG. 5 is a left-side view thereof.

The rear and bottom of the control panel is not seen during ordinary use and forms no part of the claimed design.

1 Claim, 5 Drawing Sheets
